UNITED STATES PATENT OFFICE.

MORRIS SACHS, OF ROCHESTER, NEW YORK, ASSIGNOR TO HICKOK MANUFACTURING COMPANY, INC., OF ROCHESTER, NEW YORK, A CORPORATION OF NEW YORK.

BELT FOR PERSONAL WEAR.

Application filed May 28, 1926. Serial No. 112,254.

The present invention relates to belts for personal wear and an object of the invention is to provide a construction which will be ornamental in appearance and inexpensive 5 to manufacture. Another object of the invention is to provide a composite belt structure which may be readily assembled by machinery.

To these and other ends, the invention 10 consists of certain parts and combinations of parts, all of which will be hereinafter described; the novel features being pointed out in the appended claims.

In the drawings:—

15 Fig. 1 is a face view of a belt constructed in accordance with this invention;

Fig. 2 is an edge view of the belt;

Fig. 3 is an enlarged fragmentary view of the belt; and

20 Fig. 4 is an enlarged section on the line 4—4, Fig. 3.

In the illustrated embodiment of the invention, there is provided a body member 1 formed of canvas or other heavy material 25 in strip form. The opposite faces of this body member are coated with an adhesive. One face of this body member 1 is covered by a strip 2 of thin textile fabric such, for instance, as silk. The edges of this covering 30 piece are turned inwardly at 3 about the edges of the strip 1 to overlay the strip 1 on the opposite face of the latter. Between the inturned edges 3 of the thin strip 2, an ornamenting strip 4 35 is positioned which may be of any suitable material. In this instance, this strip is an ornamented silk piece. The piece 4, the piece 1 and the piece 2 are so arranged that they may be fed through a machine which 40 will lay the strip 4 and the strip 2 on opposite sides of the strip 1 and will, at the same time, turn the edges of the strip 2 about the edges of the strip 1, the adhesive on the strip 1 holding these pieces together 45 so that they pass from the assembling machine properly united. Two facing strips 5 of leather or other suitable material are then applied to the front side of the structure thus provided so as to cover the joints between the inturned edges 3 of the piece 2 and the edges of the strip or piece 4, the piece 5 being stitched preferably in two lines of stitching 6 and 7, one line passing through the piece 5, the edge of the strip 4, the piece 50 1 and the main portion of the piece 2, and

the other line 7 of stitching passing through a strip 5, the inturned edge 3, the body 1 near the edge of the latter, and the main portion of the strip 2. These two strips 5 preferably have their outer edges coincident 60 with the outer edges of the covering 2, entirely covering the inturned portions 3 and at their inner edges covering the edges of the strip 4. It will thus be seen that when the belt is viewed from the front the leather 65 strips 5 and the silk ornamenting portion 4 will be the only parts visible, thus providing a belt which is ornamental in appearance and at the same time simulating a leather construction. An end piece 8 may be provided formed of leather and split at one end to provide two lips 9 between which the main portion of the belt is introduced and is secured by a line of stitching 10. This end piece may be provided with openings 11 for 70 the reception of the tongue of a buckle. The buckle, in this instance, is what is known to the trade as a tongue buckle, as illustrated at 12, its cross bar 13 being held within a loop having two portions 14 lying on opposite sides of the opposite end of the belt structure and secured to the latter by the stitches 15.

What I claim as my invention and desire to secure by Letters Patent is:— 85

1. A belt for personal wear comprising a body piece, a covering piece covering the rear face of the body piece and turned at its opposite edges over the inner face of the body piece, an ornamenting strip arranged between the inturned edges of the covering piece, and facing strips secured over the inturned edges of the covering piece and the edges of the ornamenting strip. 90

2. A belt for personal wear comprising 95 a body strip, a covering strip covering the rear face of the body strip and having its edges turned over the inner face of said body strip, two facing strips covering the turned edges of the covering piece, and ornamenting means interposed between the two facing strips. 100

3. A belt for personal wear comprising 105 a body strip provided with an adhesive on opposite faces thereof, a covering piece covering the rear face of the body strip and having its opposite edges turned over the inner face of said body strip, said covering strip being held to the body strip by the adhesive, two facing strips covering the in- 110

turned edges of the covering strip and spaced apart, and an ornamenting means interposed in the space between the edges of the facing strips.

- 5 4. A belt for personal wear comprising a body strip provided with adhesive on opposite sides thereof, a covering strip covering the rear face of said body strip and having its edges turned over the inner face 10 of said body strip, said covering strip being held to the front and rear faces of the body strip by the adhesive, an ornamenting strip held by the adhesive to the inner face of the body strip between the inturned edges 15 of the covering strip, two facing strips having their adjacent edges spaced apart, said facing strips covering the joints between the inturned edges of the covering strip and the edges of the ornamenting strip, and two 20 rows of stitching passing through each facing strip, one passing through each facing strip, one passing through the ornamenting strip, the body strip and the covering strip, and the other passing through an inturned 25 edge of the covering strip, the body strip and the main portion of the covering strip.

5. A belt for personal wear comprising a body strip, a cover strip covering the rear

face of the body strip and having its edges turned over the inner face of the body strip, 30 an ornamenting strip arranged on the inner face of the body strip between the inturned edges of the covering strip, and two facing strips having their adjacent edges spaced apart opposite the ornamenting strip and 35 covering the joints between the ornamenting strip and the inturned edges of the covering strip.

6. A belt for personal wear comprising a body strip having adhesive on the inner face 40 thereof, an ornamenting strip of less width than the body strip, two facing strips having their outer edges substantially coincident with the outer edge of the body strip, and their inner edges extending over the edges 45 of the ornamenting strip and spaced apart to expose such ornamenting strip, and two rows of stitching for securing a facing strip to the body strip, one passing through a facing strip near the inner edge of the latter 50 and also through the ornamenting strip and the body strip, and the other passing through a facing strip near the outer edge of the latter and through the body strip.

MORRIS SACHS.
